(57) **CLAIM**

We claim the ornamental design for a door light frame, as
shown and described.

DESCRIPTION

FIG. 1 is a front elevation view of a door light frame.

FIG. 2 is a cross sectional view taken along line 2-2 of FIG. 1.

FIG. 3 is an enlarged fragmented front perspective view of the

top end illustrated in FIG. 2.

FIG. 4 is an enlarged fragmented front perspective view of the
bottom end illustrated in FIG. 2.

FIG. 5 is an enlarged fragmented front elevation view of the
top end illustrated in FIG. 3.

FIG. 6 is an enlarged fragmented front perspective view of the
bottom end illustrated in FIG. 4.

FIG. 7 is a bottom plan view of FIG. 5.

FIG. 8 is a top plan view of FIG. 5.

FIG. 9 is a left side view of FIG. 5; and,

FIG. 10 is a right side view of FIG. 5.
